(57) **CLAIM**

The ornamental design for a motor actuator, as shown and described.

DESCRIPTION

FIG. 1 is a front elevational view of a motor actuator showing my new design;

FIG. 2 is a rear elevational view thereof;

FIG. 3 is a left side view thereof;

FIG. 4 is a right side view thereof;

FIG. 5 is a plan view thereof;

FIG. 6 is a bottom plan view thereof;

FIG. 7 is a view showing the front, plane, and right side thereof; and,

FIG. 8 is a view showing the rear, right side, and bottom thereof.

The broken lines indicate environmental structure only, and form no part of the claimed design.
